UNITED STATES PATENT OFFICE.

JOHN P. LANGFELDER, OF JAMAICA, NEW YORK, ASSIGNOR, BY MESNE ASSIGNMENTS, TO CURTISS AEROPLANE AND MOTOR COMPANY, INC., OF GARDEN CITY, LONG ISLAND, NEW YORK, A CORPORATION OF NEW YORK.

FLOTATION BODY FOR HYDROAIRCRAFT.

Application filed November 29, 1922. Serial No. 604,063.

To all whom it may concern:

Be it known that I, JOHN P. LANGFELDER, a citizen of the United States, residing at Jamaica, in the county of Queens and State 5 of New York, have invented certain new and useful Improvements in Flotation Bodies for Hydroaircraft, of which the following is a specification.

My invention relates to body construction 10 and more particularly to flotation body construction of the pontoon type.

The invention is characterized by an all-metal body construction in which the skeleton framework as well as the outer covering 15 is formed wholly of metal, preferably duralumin; the disposition of the frame members and the arrangement of the cover sheets being such that ease of assembly and accessibility are dominant factors in the design.

A further characteristic of the invention is the formation of the center line frame member or keelson in the form of a trussed beam, said keelson embodying a top chord of 25 channel section, a bottom chord of channel section, and a plurality of chord-connecting members having their ends extended into the channels of said chords.

A still further characteristic of the invention 30 is the provision of transverse formers and transverse bulkheads, the formers comprising metal strips of unbroken continuity and of channel section, and the bulkheads comprising sheet metal plates flanged 35 marginally to provide with the channeled formers suitable metal bearing surfaces against which the metal covering is laid and fastened.

Other characteristics of the invention, 40 such for instance as the flanging of the cover sheets, the keel formation, the reinforcements obtained by crimping the metal parts, the internal bracing, etc., will be hereinafter more fully described.

A float or body thus characterized is exceedingly light, exceptionally strong, and highly adapted to quantity production at 45 minimum manufacturing cost.

In the drawings, wherein like reference 50 characters denote like or corresponding parts:

Figure 1 is a side elevation of the forward

portion of the float or body, the outer covering thereof being partly broken away;

Figure 2 is a side elevation of the aft 55 portion of the float or body;

Figure 3 is a detail perspective view of the center portion of the keelson;

Figure 4 is a detail perspective view showing the relation between one of the 60 transverse bulkheads, the keelson, and the outer covering of the float;

Figure 5 is an enlarged transverse vertical sectional view of the float;

Figure 6 is a detail side elevation of that 65 portion of the interior framework of the pontoon or float into which the forward diagonal supporting strut extends;

Figure 7 is a section on the line 7—7 of Figure 5;

Figure 8 is a section on the line 8—8 of Figure 5;

Figure 9 is a transverse vertical sectional view of the float showing in detail the construction of one of the transverse formers; 75

Figure 10 is a fragmentary plan view of the nose portion of the float;

Figure 11 is a longitudinal vertical sectional view of that portion of the float illustrated in Figure 10; and 80

Figure 12 is a detail sectional view of one of the hand-hole covers.

In the embodiment of the invention selected for illustration a pontoon float for hydroaeroplanes is shown. The invention, 85 while particularly adapted to this type of float, is nevertheless characterized by certain constructional features applicable to other and different types of flotation bodies, even to the flying-boat hull. For this reason, the term "flotation body" used in the claims is intended to cover any and all types of floats.

As shown, the pontoon, in side elevation, is of more or less conventional form. Its under surface is preferably V shaped in cross-section throughout substantially the full length of the float. Intermediately of its ends said bottom surface is provided with a rearwardly facing step 10; that portion of said bottom surface in advance of the step being designated as 11 and constituting what will be hereinafter referred to as the hydroplaning surface of the float bottom. From

the step forwardly the hydroplaning bottom surface 11 extends horizontally to a point well forward, from which point said bottom is inclined upwardly and forwardly to the 5 extreme nose of the float. From the step rearwardly the bottom of the pontoon is inclined upwardly and rearwardly, such upwardly inclined bottom surface being designated as 12. The deck of the pontoon, from 10 nose to stern, is preferably continuously curvalinier in transverse section, the curvature, forward of the step, terminating at the chines, and aft of the step, terminating at the gunwales which (see Fig. 2) are inclined 15 upwardly and rearwardly from the outer step ends to the upper end of the stern. At the stern the pontoon terminates in a substantially vertical edge. In other words, 20 from the stern forwardly, the sides of the pontoon gradually wash out to a point of merger at the step.

The framework of the pontoon, as well as the outer covering, is constructed entirely of metal. Said framework includes as its 25 backbone a center-line frame member or keelson designated in its entirety as 13. In its preferred embodiment the keelson comprises a top chord 14 of channel section and a bottom chord 15, likewise of channel section, each channel having its open side directed inwardly. The top chord 14 of the keelson, from end to end, is unbroken in its continuity, whereas the bottom chord 15, as distinguished from the top chord, is 30 broken at the step. At the step 10 the frame sections which comprise the bottom chord 15 overlap, that portion of the bottom chord 15 extending throughout the length of the aft portion of the float being enlarged in 35 depth at its forward end as at 16 to fit within the channel of that portion of the bottom chord forward of the step (see Fig. 3). From end to end the chords 14 and 15 of the keelson are inter-braced by vertical members 40 17 and diagonal brace members 18, said members being in each instance of channel section and so disposed relatively to the chords 14 and 15 as to enter the channels thereof at their opposite ends. The diagonal 45 frame members 18 are fastened together at their points of inter-section and within the channels of the chords 14 and 15 at their 50 opposite ends.

The top chord 14 of the keelson is laterally 55 flanged as indicated at 19 except at the points where the chord-connecting members 17 and 18 enter the channels of the chords. At such points, the chord 14 is characterized 60 by an absence of lateral flanges and an increased channel depth. Such construction is conducive to maximum strength.

The bottom chord 15, aft of the step 10, 65 is identical in construction with the top chord 14, though of a somewhat different construction throughout that portion of its

length forward of the step. The latter portion of the bottom chord 15 is laterally flanged as at 20, the flanges being oppositely directed and continuous from end to end throughout the full length of the forward portion of the bottom chord. Thus organized, the flanges 20 provide the necessary flat bearing surfaces to which the bottom covering of the float is attached. Upon reference to either Figure 4, Figure 5, or Figure 9, it 70 will be noted that the bottom chord 15, forward of the step, is projected beneath the hydroplaning bottom surface 11, such projected or extended portion providing a keel for the float. 75

At intervals of space throughout the length of the keelson 13 formers 21 and bulkheads 22 are provided, the latter being watertight, to the end that the pontoon may have a plurality of water-tight compartments. 80 The bulkheads 22 are in each instance of identical construction. Each (see Fig. 4) comprises a single metal sheet having a marginal lateral flange 23 extended throughout its entire periphery. Centrally each bulkhead 22 is fastened against one of the vertical frame members 17 of the keelson as well as the top and bottom chords thereof, and at each side of the vertical center-line of the bulkhead the metal plate of which 85 it is composed is crimped as at 24, the crimps being angularly directed symmetrically at opposite sides of said center-line to better distribute the stresses incurred in the actual use of the float. Preferably the crimps 24 extend angularly away from the float bottom inwardly toward the keelson. 90

The formers 21, unlike the bulkheads 22, are of framed construction. Each comprises a single length of metal strip, preferably 105 of channel section, flattened at the chine lines of the hull as indicated at 25 as well as at the points of intersection with the keelson. The ends of the metal strip are fastened to the bottom chord 15 of the keelson, i. e., to the flanges 20 thereof, forwardly of the step, and to the base portion of the channel of both the top and bottom chords 15 and 16 rearwardly of said step; 110 such arrangement being desirable for reasons stated hereinbefore. From the chine lines, each former 21 is braced diagonally inwardly as at 26 to the keelson and diagonally inwardly as at 27 intermediately of the chine lines and the keel or center-line 115 of the float. The braces 26 and 27 are also of channel section except at the ends of the braces, the latter being flattened as indicated. Formers thus constructed are extremely 120 light and exceptionally strong, and as a result of the single length of metal strip used in their construction, the formers may be 125 very economically manufactured.

Collectively the formers 21 and the bulkheads 22, together with the keelson 13, con- 130

stitute the skeleton framework over which the outer covering for the float is laid. Said outer covering preferably comprises a plurality of metal sheets riveted together along 5 their longitudinal abutting edges and to the frame members comprised in the pontoon skeleton. The top covering consists of two side sheets 28 and a top sheet 29, the latter being extended across the top of and upon 10 the outside of the keelson and having its edges out-turned or flanged as indicated at 30. The side sheets 28 have flanges 31 which are out-turned to abut the flanges 30 of the top sheet 29, and along their bottom 15 edges overlap the two sheets 32 which constitute the bottom covering. Said bottom cover sheets 32 are fastened to the flanges 20 of the bottom chord of the keelson and to the bottom edges of the side sheets 28, 20 the fastening in the latter instance following the chine lines of the float or body.

As a reinforcement, the cover sheets 28 are crimped as at 33 longitudinally of their 25 length and intermediately of their edges, whereas the bottom sheets 32, instead of being crimped as a reinforcement, are provided each with a crimped strip 34 fastened upon their under-surface.

The bottom cover sheets 32, unlike the 30 sheets provided for the curved portion of the skeleton framework, are carried to the ends of the pontoon, whereas the latter terminate short of the ends, preferably in line with one of the bulkheads. The covering 35 for the framework respectively fore and aft of the points mentioned is formed by single sheets 35 and 36, the former being conformed to the nose shape of the pontoon and the latter to the stern shape thereof.

40 As it is customary in pontoon construction to provide a plurality of supporting struts, provision is made within the pontoon, as an integral part of the skeleton framework, for the attachment of the lower 45 strut ends. The struts, designated as 37 and 38, are preferably inclined to the vertical. Each strut comprises side plates 39 and edge plates 40, the latter being fitted between the side plates and flanged as indicated at 41 (see Fig. 7). Over the hollow strut thus constructed suitable fairing may be placed if desired.

At the points where the strut ends enter the pontoon, inclined or diagonal transverse 50 brace members 41 are provided, each of said brace members comprising a flat metal sheet flanged in a manner similar to the bulkheads 22, though provided with lightening holes 42. The strut ends enter the pontoon 55 between the plates 41 and extend throughout the full depth thereof, terminating at the bottom chord of the keelson. Preferably the plates 41 are stiffened through the use of diagonally disposed stiffeners 43 arranged as indicated. The plates between

which the strut ends are disposed are in each instance inclined in the direction of the struts, and to provide for a simple, yet rigid fastening, the plates 39 are flanged as at 44 to bear directly against the plates 41 between which the struts are fitted. 70

To admit of access to the pontoon interior, a plurality of arm or hand-holes 45 are provided, one preferably in each watertight compartment. Over the hand-holes 75 45 hand-hole cover plates 46 are fastened. The cover plates 46 are preferably constructed of some such flexible material as rubber, peripherally enlarged as at 47 and provided with an inner annular groove 48. 80 Within the groove 48 an annular bead 49 is fitted, said bead being carried by the outer covering of the pontoon in the manner indicated in Figure 12. Hand-hole cover plates thus organized will adapt themselves in 85 form to the exterior form of the float, and by reason of the yielding material of which they are constructed, may be easily snapped in place to be held by the engagement between the bead 49 and the annular groove 90 48 into which the bead is fitted.

As a further reinforcement for the float covering, channeled strips 49' may be provided to receive the abutting flanges of the cover sheets 28 and 29. Such strips 49 (see 95 Fig. 4) extend throughout the length of said flanges and in each instance are flattened at their terminals and directly riveted to the covering. There is also provided internally of the pontoon, suitable brace means 50 100 in the vicinity of that portion of the pontoon designed to withstand the catapult strains if the machine upon which the float is used is to be catapulted. Moreover, for ease in towing, a tow-ring 51 may be integrally fastened at the nose end of the pontoon as indicated. Preferably the tow-ring 51 is provided with a base casting 52 shaped to conform to the nose shape of the pontoon. Internally said casting 52 is provided with 105 a center flange 53 to which the top chord of the keelson is riveted. Moreover, by reason of its disposition at the extreme nose, said casting provides also a flat bearing surface against which the bottom cover sheets are 110 adapted to be fastened. A tow-ring thus constructed is especially desirable in that the towing stresses or strains are carried and distributed throughout not only the skeleton framework of the pontoon but 115 throughout the covering thereof as well; the latter, by reason of its rigidity, being serviceable as a strength giving element of the float.

While I have described my invention in 120 detail in its present preferred embodiment, it will be obvious to those skilled in the art after understanding my invention, that various changes and modifications may be made therein without departing from the spirit or

scope thereof. I aim in the appended claims to cover all such modifications and changes.

What I claim is:—

6. 1. In a flotation body for hydroaircraft, a skeleton framework including a metallic keel of channel section and a keelson of which said keel forms a part, portions of said keelson being extended into and fastened within the channel of said keel.

10. 2. In a flotation body for hydroaircraft, a skeleton framework including a metallic keel of channel section and a trussed metallic keelson of which said keel forms a part, portions of the truss embodied in said keelson being extended into and fastened within the channel of said keel.

15. 3. In a flotation body for hydroaircraft, a skeleton framework including a trussed keelson comprising a top chord, a bottom chord, and a plurality of chord-connecting members, said chords, in each instance, being of channel section and so disposed relatively to each other as to receive in the channels thereof the ends of the chord-connecting members, and an outer covering for the skeleton framework entirely enclosing said keelson except for that portion of the bottom chord which functions also as a keel for the flotation body.

20. 4. In a flotation body for hydroaircraft, a skeleton framework including a trussed keelson comprising a continuous top chord, a bottom chord having an intermediate break in its continuity, and a plurality of chord-connecting members, said chords, in each instance, being of channel section and so disposed relatively to each other as to receive in the channels thereof the ends of the chord-connecting members, and an outer covering for the skeleton framework entirely enclosing the top chord and that portion of the bottom chord aft of its intermediate break, said bottom chord, forward of said intermediate break, being exposed and extended beneath said outer covering to provide a keel for the flotation body.

25. 5. In a flotation body for hydroaircraft, a skeleton framework including a trussed keelson comprising a top chord, a bottom chord, and a plurality of chord-connecting members, said chords, in each instance, being of channel section and said bottom chord being provided with outwardly directed flanges, and an outer covering for the framework fastened to the base portion of the channel of the top chord and to the flanges of the bottom chord, said top chord being thereby entirely enclosed within said outer covering, whereas said bottom chord is projected therebeneath.

30. 6. In a flotation body for hydroaircraft, a skeleton framework including a trussed keelson comprising a top channelled chord, a bottom channelled chord and chord-connect-

ing members having their opposite ends extended into the channels of said chords, and transverse formers distributed longitudinally of the length of said keelson, the formers in each instance comprising a single metal strip of channel section throughout substantially its full length.

7. In a flotation body for hydroaircraft, a skeleton framework including a trussed keelson, and a plurality of water-tight bulkheads distributed longitudinally throughout the length of said keelson, each bulkhead comprising a single metallic plate, crimped without being perforated, for added strength.

8. In a flotation body for hydroaircraft, a skeleton framework including a keelson and a plurality of metallic formers distributed longitudinally of its length, each former comprising a single metallic strip of channel section having its open side facing inwardly, and an outer covering for the framework fastened to the formers, the base portion of the channel of each strip offering a bearing surface against which the outer covering is laid.

9. In a flotation body for hydroaircraft, a skeleton framework including a keelson and a plurality of formers distributed longitudinally of its length, said formers comprising in each instance a single channel strip flattened intermediately of its ends to lie flat against the top edge of said keelson.

10. In a flotation body for hydroaircraft, a skeleton framework including a trussed keelson comprising a top channel chord, a bottom channel chord and a plurality of chord-connecting members engaging in the channels of said chords, and a plurality of formers distributed longitudinally throughout the length of said keelson, each former comprising a channel strip flattened at its point of contact with the top edge of said keelson and with the top edge of the bottom chord of said keelson, the formers in each instance at their points of engagement with the top edge of said keelson being unbroken in continuity.

11. In a flotation body for hydroaircraft, a skeleton framework including a plurality of metallic transverse bulkheads, each bulkhead being crimped for added strength, and an outer metallic covering for the framework fastened to the bulkheads, said outer metallic covering being likewise crimped for added strength in a longitudinal direction.

12. In a flotation body for hydroaircraft, a skeleton framework including a metallic keelson provided with flat bearing surfaces along its top edge and adjacent to its bottom edge, transverse formers distributed longitudinally throughout the length of said keelson, each of said formers being likewise provided with flat bearing surfaces through-

- out their respective peripheries, and an outer covering for the framework fastened to the bearing surfaces of the keelson and of the formers.
- 5 13. In a flotation body for hydroaircraft, a skeleton framework including a plurality of transverse formers, each comprising a single length of metal strip bent and flattened at the chines, and flattened at the 10 keel, each strip, intermediately of said flattened portions, being of true channel section.
14. In a flotation body for hydroaircraft, a skeleton framework including a center keelson and a plurality of transverse formers 15 distributed longitudinally throughout the length thereof, each former comprising a single length of metal strip bent and flattened at the chines and flattened at the points 20 of intersection with the keelson, each strip intermediately of said flattened portions being of true channel section.
15. In a flotation body for hydroaircraft, a skeleton framework including a centrally disposed longitudinally extending vertical 25 frame member of substantially the full depth of the float, and a plurality of transverse formers distributed longitudinally throughout the length of said frame member, each former comprising a single length 30 of metal strip bent and flattened at the chines of the float, flattened at the points of intersection with said vertical frame member, and of channel section intermediately of said flattened portions, that por- tion of each former extending across the 35 bottom portion of the float being diagonally braced to said longitudinal frame member, the braces in each instance being of channel section and provided with flattened ends which bear respectively against the formers and the frame member.
16. A hand-hole cover for enclosed bodies comprising a flexible disk adapted due to its flexibility to conform to the exterior surface of said body together with retaining 40 means for holding the cover disk in place.
17. A hand-hole cover for enclosed bodies comprising a rubber disk adapted to conform to the exterior surface of said body together with a snap retaining means for 45 holding the rubber disk in place.
18. A hand-hole cover for enclosed bodies comprising a flexible disk adapted to conform to the exterior surface of said body, and a retaining means for the disk comprising a circular bead over which the disk is snapped.
19. A hand-hole cover for enclosed bodies comprising a flexible disk provided with an enlarged periphery having an annular 50 groove formed therein together with a retaining means for said disk comprising an annular bead projecting outwardly from the body for engagement in said groove.
- In testimony whereof I hereunto affix my 55 signature.

JOHN P. LANGFELDER.
